Primary Examiner — Lucy Lieberman(74) *Attorney, Agent, or Firm* — Carmody & Torrance LLP(57) **CLAIM**

The ornamental design for a watch casing, as shown and described.

DESCRIPTION

FIG. 1 is a perspective view of a watch casing showing my new design;

FIG. 2 is a right side elevational view thereof;

FIG. 3 is a left side elevational view thereof;

FIG. 4 is a first end elevational view thereof;

FIG. 5 is a second end elevational view thereof;

FIG. 6 is a top plan view thereof; and,

FIG. 7 is a bottom plan view thereof

The broken line showings are environmental only and form no part of the claimed design.
